UNITED STATES PATENT OFFICE.

VINCENZO BENEDETTI, OF PALISADE, NEW JERSEY.

SHOE-RETAINER.

1,277,177.

Specification of Letters Patent. Patented Aug. 27, 1918.

Application filed September 21, 1917. Serial No. 192,581.

To all whom it may concern:

Be it known that I, VINCENZO BENEDETTI, a citizen of the United States, and a resident of Palisade, in the county of Bergen and State of New Jersey, have invented a new and Improved Shoe-Retainer, of which the following is a full, clear, and exact description.

Among the principal objects which the present invention has in view are: to retain the heel of a shoe firmly in service position on the foot; and to provide independent means for holding a shoe in the position set forth.

In the drawings, the figure is a side view of a retainer constructed and arranged in accordance with the invention, showing the adaptation of the retainer to a skate shoe.

In a retainer constructed and arranged as shown in the drawing, an arch strap is provided, the loose end 16 being arranged to en-

gage a buckle 17 on the body 18 of the retainer. The necessity for this arrangement arises when the shoe 19 is permanently attached to another article such as a skate 20. 25

The upward extension of the body 18 and the provision of openings 21 form pockets for the ankle bones of the wearer.

It will be observed that the invention provides a buckle 22 and a strap end 23 disposed on the ankle above the instep of the wearer.

Claim:

A shoe retainer comprising a supporting section provided with openings to receive the ankle joints of the wearer, said section partially covering the counter and rear of a shoe in service; strap ends extending from said section for encircling the ankle of the wearer; and means extending below the arch of said shoe for holding the retainer in place.

VINCENZO BENEDETTI.
